US0D1023769S

(12) **United States Design Patent** (10) **Patent No.:** **US D1,023,769 S**
(45) **Date of Patent:** **** Apr. 23, 2024**

(54) **SURFACE ORNAMENTATION FOR A BOTTLE**

(71) Applicant: **Diageo North America, Inc.**, New York, NY (US)

(72) Inventors: **Christopher Jenkins**, London (GB); **Alistair Colvin Horne**, Bethel, CT (US)

(73) Assignee: **DIAGEO NORTH AMERICA, INC.**, New York, NY (US)

(**) Term: **15 Years**

(21) Appl. No.: **29/797,666**

(22) Filed: **Jul. 1, 2021**

(51) LOC (14) Cl. **09-01**

(52) U.S. Cl.

USPC **D9/566**

(57) **CLAIM**

The ornamental design for a surface ornamentation for a bottle, as shown and described.

DESCRIPTION

FIG. 1 is a front perspective view of a surface ornamentation for a bottle showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines are shown for the purpose of illustrating parts of the article that form no part of the claimed design.

1 Claim, 5 Drawing Sheets
